UNITED STATES PATENT OFFICE

141,150

DESIGN FOR A COMBINED BOOK END AND HOLDER FOR A MAGAZINE OR SIMILAR ARTICLE

Harry Poschin, Pasadena, Calif.

Application November 21, 1944, Serial No. 116,464

Term of patent 14 years

(Cl. D33—3)

To all whom it may concern:

Be it known that I, Harry Poschin, a citizen of the United States, residing at Pasadena, in the county of Los Angeles and State of California, have invented a new, original, and ornamental Design for a Combined Book End and Holder for a Magazine or Similar Article, of which the following is a specification, reference being had to the accompanying drawing forming a part thereof.

and holder for a magazine or similar article showing my new design with the curved support in a slightly raised position;

I claim:

The ornamental design for a combined book end and holder for a magazine or similar article, as shown.

HARRY POSCHIN.
